LIGHT SOCKET RETAINER

This application is a continuation-in-part of copending application Ser. No. 739,433 filed June 24, 1968 now abandoned.

BACKGROUND OF THE INVENTION

This invention relates to an improved light socket retaining means for hanging strings of lights and other ornaments, and, more particularly, the invention is directed to a means for securing a continuous strand of lights to the ceiling or wall of a house or other structure. The invention provides for a base element which may be securely mounted to a house or like structure and which is adapted to receive and securely support a removable clip-type socket holder adapted to retain an electrical light socket firmly therein.

An occupant desiring to decorate his residence or place of business during Christmas or some other occasion often mounts decorative lights around the outside or within the building. Strands of decorative lights are commonly provided with continuous conductive wiring along which light sockets that are located at regular intervals and which accommodate decorative electric lamps or bulbs. Spacing of the sockets in such light strings is not standardized nor necessarily uniform within a given string nor do the sockets exhibit uniform configurations. Mounting means commonly provided on light strings, such as spring clips, are intended for and adapted to mounting the lights to tree limbs rather than to the flat surfaces normally encountered about a building and are thus unsuitable for such application.

Despite the widespread practice of decorating houses, both inside and outside, with strands of light, no universally satisfactory solution is presently available for mounting the lights. Each user is thus left to his own devices in mounting light strings to his house or other structure. A usual practice is to suspend the lights by their conductive wiring from nails or other fasteners secured to the building. Such practices have proved far from satisfactory as being an unsightly, temporary and even dangerous expedient. Abrasion and fraying of the electrical insulation in the area of contact between wiring and the support is likely and may result in short circuits and the attendant fire hazards, especially where the apparatus is suspended from metallic fasteners.

In U.S. Pat. No. 3,193,229 to Stock, the use of a nonconductive hook is taught for suspension of light stands from the rain gutter of a home. Although reducing the hazard of electrical shorting, the hanger still supports the light by the electrical wiring leaving the sockets containing the fragile bulbs to swing freely in the wind and possibly sustain damage by impact with adjacent structures. Seasonal precipitation, common when outside decorative lighting is employed, can also be detrimental to lighting equipment. The sockets, electrical connections therein, and electrical contacts with the bulbs are particularly susceptible to corrosion and water damage. Where suspended by the interconnecting wiring the sockets and bulbs normally occupy the low points, between supports, at which precipitation naturally collects, an obviously undesirable situation. The hanger taught by Stock is further limited to use in conjunction with rain gutters and does not lend itself to mounting lights to the eaves where no gutters exist, to the gables, or to surfaces within the house.

In U.S. Pat. No. 3,189,310 to Trueson, a holder is disclosed for mounting Christmas lights by the sockets and thus circumvents the problems attendant to support by the wiring. Trueson's holder retains the light sockets by friction and in other than an upright orientation the sockets may become disengaged from the holder due to vibration or forces induced by the free swinging wiring between supports. The holder taught by Trueson is particularly adapted for use with sockets from which the wiring extends laterally and may not accommodate sockets commonly provided with wiring connections at their bases. There is no standardization of external configuration nor size of light sockets which in addition to presence of mounting clips may limit applicability of a holder required to fit a socket closely.

Numerous disadvantages are thus apparent in the prior art which limit application of existing mounting means according to light socket characteristics or the possibility of damage to wiring or electrical and structural integrity of light strands commonly available.

OBJECTS OF THE INVENTION

It is therefore an objective of the present invention to provide a convenient reusable mounting means by which a decorative string of lights may be readily affixed to any substantially flat surface.

Another object is to provide a mounting means by which the most advantageous orientation of the bulbs may be maintained.

Another objective is to provide a mounting means by which the light sockets are securely held to reduce damage to the fragile bulbs and loosening thereof within the sockets.

Another objective is to provide a mounting means by which a strand of lights may be subjected to the least damage or deterioration from the natural elements commensurate with use.

A further objective is to provide a mounting means which does not result in chafing, wear or breakage of the electrically conductive wiring.

A still further objective is to provide a mounting means which will hold the light sockets securely regardless of variations in conformation and placement of electrical wiring thereto.

A still further object is to provide a mounting means which, when not in use, is unobtrusive and does not materially detract from the appearance of the surface of structure upon which situated.

A still further object of the present invention is to provide a novel mounting means having a base member which may be permanently secured to a mounting surface and a socket holder which may be detached from the base member when not in use.

SUMMARY OF THE INVENTION

This invention contemplates the use of a series of light mounting means so located as to match the spacing and desired positioning of the light sockets of a strand of decorative lights.

Each mounting means has a base element fixed more or less permanently to a substantially flat surface of a building and a clip-type light socket holder which attaches to the base element.

The base element is affixed to the building surface by adhesive, staple or other appropriate fastening means and provides a pair of slideways by which a light socket holder is releasably supported. The light socket holder includes flanges for engaging said slideways for support thereby, and has a pair of flexible arcuate clips which receive and firmly retain a light socket therein.

Other objects and advantages of the invention will become readily apparent from the following description of preferred embodiments of the invention when read in connection with the accompanying drawings in which:

BRIEF DESCRIPTION OF THE DRAWINGS

FIG. 1 is a fragmentary perspective view of a house showing a plurality of light socket retainers employed in fixing a string of lights to the eaves, gable and other surfaces of the house;

FIG. 2 is a perspective view of the light socket retainer as mounted to a horizontal surface;

FIG. 3 is a side elevational view of the light socket retainer fastened to a vertical surface;

FIG. 4 is a perspective view of another embodiment of the invention showing the light socket holder detached from the base member;

FIG. 5 is a bottom plan view showing the underside of the socket holder perspective illustrated in FIG. 4; and

FIG. 6 is a side view of the socket holder illustrated perspective in FIG. 4.

DESCRIPTION OF THE PREFERRED EMBODIMENT

Referring now to the drawing in which like reference characters designate like parts, and particularly to FIG. 1, there is shown a fragmentary perspective view of a house 10 with strands of decorative lights 20 mounted thereon. The light socket retainer 30 herein disclosed is employed to mount the decorative lights to the eaves 11, gable 12 and about opening 13 of the house. Trim and moldings at such locations provide substantially flat surfaces to which the light socket retainers 30 are attached. The light socket retainers 30 may be affixed to any reasonably flat surface and may thus be employed to attach strands of decorative lights to walls, ceilings or other surfaces in artistic or decorative patterns or to provide special lighting effects.

Strands of decorative lights 20 characteristically have light sockets 21 spaced along conductive wiring 22 which provide mechanical support for electrical lamps or bulbs 23 as well as conductive contact between bulbs and wiring. In practice a series of light socket retainers 30 are used to attach a string of lights to a building or structure. The light socket retainers are located according to the spacing of sockets 21 along the conductive wiring 22 and in accordance with the lighting pattern desired. Since decorative lighting is commonly used during limited seasons of the year, the retainers 30 are comprised of separable members; a base member 41 which remains attached in place on the structure and a light socket holder 51 which is removed along with the light string 20 for storage between seasons.

A preferred embodiment of the light socket retainer 30 is illustrated in FIG. 2 wherein a base member 41 and light socket holder 51 are made of a resilient structural plastic. The base member 41, shown mounted to a horizontal surface 14, is comprised of a substantially flat body portion 42 with a front surface 43 from which project two parallel and oppositely oriented channel elements forming a pair of parallel slideways 44. An attaching portion 45 is indicated extending rearwardly at substantially right angles to said body portion 42. A surface 46 is provided on attaching portion 45 for abutting attachment to substantially flat surfaces. The thickness of attaching portion 45 is sufficient to maintain structural integrity yet be readily pierced by fastening means such as wire staples, nails, screws or the like.

The base member 41 is affixed to a building or other structure by fasteners through attaching portion 45 or by adhesives applied to the surface 46 for abutting attachment to flat surfaces. A particularly convenient technique has proved to be the use of a contact cement on the surface 46 which remains covered by a protective paper until employed for attaching base member 41 to a structure.

A light socket holder 51 has flange means 52 with parallel edges dimensioned for slideway engagement with slideways 44 of base member 41. A pair of flexible arcuate-shaped clamping elements 53 extend laterally from flange means 52. The arcuate shape and flexible nature of clamping elements 53 permits considerable deformation without permanent set thus enabling clamping elements 53 to accommodate light sockets 21 of various shapes and sizes without loss of ability to firmly retain the sockets therein.

In practice, base members 41 are affixed to the building with appropriate fastening means positioned at locations selected by the user. The light socket holders 51 are secured to the base members 41 by slideway engagement therewith. The light sockets 21 are secured to the light socket holders 51 and the bulbs 23 are mounted therein. To remove a strand of lights 20 it is only necessary to slidably disengage light socket holders 51 from base members 41, the base members remaining attached to the building for reuse in again mounting lights at the selected locations. The light socket holders 51 may remain secured to the strand of lights or be removed for separate storage between uses.

Mounting versatility of the light socket retainer is illustrated in FIG. 3 wherein the invention is shown mounted to a vertical surface 15. Base member 41 is secured to vertical surface 15

by a nail 61 driven through attaching portion 45. Outwardly extending body portion 42 with slideways 44 permit slideway engagement of light socket holder 51 providing support for light socket 21 secured in an outward orientation as shown. It should be noted that other mounting orientations of the light sockets 21 are possible by providing two pairs of flanges 52 forming a square for 90° rotation of clamping elements 53 upon selection of adjacent flanges for slideway engagement with slideways 44 of base member 41.

Turning now to FIGS. 4, 5 and 6 an alternative embodiment of the present invention is shown which includes a base member 70 and a socket holder 72 adapted for mating engagement with the base member 70. Base member 70 is preferably of unitary construction having a flat base portion 74 with a pair of turned back edges 76 and 78 which form slideways for receiving the flanges 80 of socket holder 72. The lower ends of the slideways are closed as indicated at 82 so as to prevent the flanges 80 from passing out of the lower side of the slideways. In addition, to aid in securing the holder 72 in engagement with the base member 70, the edges 84 are tapered so as to wedgedly engage the shoulders 86 of the holder 72. Holes 88 may be provided in the base portion 74 for securing the base member to a given surface by nailing or screwing, or an adhesive may be used as the securing medium.

Projecting from the flanged portion 90 of the holder 72 is a rib 92 which connects the arcuate socket engaging portion 94 to the flanged portion 90. The arcuate portion 94 terminates in a pair of diverging tabs 96 which aid in aligning a light socket which is to be snapped into mounting engagement with the arcuate portion 94 in a manner similar to that illustrated in FIG. 2. Furthermore, the tabs 96 act as camming means for causing the gap 97 between the arcuate limbs 94 open to allow a light socket to snap into engagement with the socket holder. In order to add additional strength to the base portion 90, the rib 92 and the arcuate portions 94, an integrally formed web 98 is provided at the top of the holder 72. The additional rigidity provided to the holder structure by the web 98 enables the device to be formed of lighter, more flexible material such as nylons and other plastics which would otherwise be less suited to this particular application.

In use, the base member 70 is appropriately positioned and secured to the desired surface. The socket holder 72 is then aligned as illustrated in FIG. 4 so that the flanges 80 may be received within the slideways of the base member 70. The holder 72 is then forced into mating engagement with the base member 70 and will be securely retained therein by the frictional engagement between the edges 84 of the base member and the shoulders 86 of the holder 72. Once so positioned, a lamp socket can be forced into clamping engagement with the arcuate portion 94 which will securely hold the lamp socket in position. It should be noted that a relatively wide range of socket diameters and noncylindrical configurations can be accommodated.

When the holder is no longer needed it may be removed from engagement with the base member by a simple lifting force applied thereto and may be stored with the lamp apparatus until the following season. By making the base member 70 out of a transparent or semitransparent material such as nylon it can be very inconspicuously left in place and need not be removed. This feature makes subsequent installation of the decorative lights quite simple while at the same time eliminating unsightly brackets or nails which may rust and discolor the wall or trim to which the lights are mounted.

Whereas certain forms of the invention have been shown and described, they should be taken in an illustrative or diagrammatic sense only. It is contemplated that there are many variations and modifications which will be apparent to those skilled in the art which will not depart from the scope and spirit of the invention. I, therefore, do not wish to be limited to the precise details of construction set forth, but desire to avail myself of such variations and modifications as fall within the scope of the appended claims.

I claim:

1. A light socket retainer comprising:

a base member including an attaching portion for abutting attachment to a substantially flat surface, and a body portion having a pair of opposed slideways; and a light socket holder including a slide portion having flange means dimensioned for slidable reception by said slideways, and a light socket engaging portion having a pair of flexible arcuate-shaped clamping elements extending laterally from said slide portion for receiving and clampingly retaining a generally cylindrically-shaped light socket in a position such that said socket is held in spaced 10 apart relationship with said slide portion and with its axis substantially parallel to a plane defined by said slideways.

2. A light socket retainer as recited in claim 1 in which said body portion extends substantially at right angles to said attaching portion.

3. A light socket retainer as recited in claim 2 wherein said flange means form a square dimensioned for slidable reception by said slideways.

4. A light socket retainer comprising:

a base member including an attaching portion having a surface for abutting attachment to a substantially flat surface, a body portion having a front surface extending substantially at right angles to said attaching portion, and two opposed channel elements projecting from said front surface forming a pair of opposed parallel slideways; and a light socket holder including a slide portion having square flange means dimensioned for slidable reception by said slideways, and a pair of flexible arcuate-shaped clamping elements extending laterally from said slide portion for receiving and clampingly retaining a light socket in a posi- 30

tion such that said socket is held in spaced apart relationship with said slide portion and with its axis parallel to a plane defined by said square flange means.

5. A light socket retainer comprising:

a base member including a flat rectangularly-shaped surface two opposite extremities of which are folded back to form a pair of slideways, said slideways being terminated at one end by an integrally formed web means; and

a light socket holder including a slide portion having flange means dimensioned for slidable reception by said slideways, an arcuate-shaped light socket engaging retainer means coupled in spaced apart relationship with said flange means by a rib means, and web means integrally formed with one side of said flange means, said rib means and said arcuate-shaped retainer means so as to give structural rigidity to said holder means.

6. A light socket retainer as recited in claim 5 wherein the extremities forming said slideways are tapered and wherein said flange means includes a pair of shoulders which frictionally engage said tapered extremities so as to secure said socket holder in said base member.

7. A light socket retainer as recited in claim 6 wherein said arcuate-shaped retainer means includes a radial projection at each arc terminus for providing a camming means for camming said arcuate-shaped retainer means outwardly as it is engaged by a light socket so as to allow the light socket to snap into mating engagement with said arcuate-shaped retainer means.
